(57) **CLAIM**

The ornamental design for a glass, as shown and described.

DESCRIPTION

FIG. 1 is a perspective view of a glass showing my new design;
FIG. 2 is a side view thereof, the opposite side being a mirror image thereof,

FIG. 3 is a top view thereof,

FIG. 4 is a bottom view thereof,

FIG. 5 is a front view thereof; and,

FIG. 6 is a rear view thereof.

The broken line showing of a coaster is included for the purpose of illustrating environmental support and forms no part of the claimed design.
